UNITED STATES PATENT OFFICE

137,502

DESIGN FOR A DEEP WATER FISHING TACKLE

Arthur E. Thompson, Marysville, Calif.

Application October 16, 1943, Serial No. 111,402

Term of patent 7 years

(Cl. 31—4)

To all whom it may concern:

Be it known, that I, Arthur E. Thompson, a citizen of the United States, residing at Marysville, in the county of Yuba and the State of California, have invented a new, original, and ornamental Design for a Deep Water Fishing Tackle, of which the following is a specification, reference being had to the accompanying drawing, forming part thereof.

Fig. 1 is a side elevational view of the Deep Water Fishing Tackle, showing my new design;

Fig. 2 is a side view thereof with pendant portions in a different position;

Figs. 3 and 4 are, respectively, top and bottom plan views with portions broken away for convenience in illustration.

I claim:

The ornamental design for a deep water fishing tackle, as shown.

ARTHUR E. THOMPSON.
